DOOR OPERATING MECHANISM

William A. Smith, Cortland, N. Y.

Application February 26, 1931, Serial No. 518,530
Renewed September 26, 1933

1 Claim. (Cl. 292—94)

This invention relates to means for releasing and opening the doors of a garage or other building of the type whereby the doors or gates automatically open upon the approach of a vehicle.

5 A primary object of the invention is to improve and simplify the construction and operation of apparatus of this character to render it reliable and efficient and yet comparatively inexpensive to manufacture and install.

10 In carrying out these objects, the invention is susceptible of a wide range of modification without departing from the spirit or sacrificing any of the advantages of the claimed invention; there being shown in the drawings for illustrative purposes a preferred and practical form, in which:

Fig. 1 represents a perspective view of a garage equipped with this door opener and with the doors shown in open position;

Fig. 2 is a horizontal section taken on the line 20 2—2 of Fig. 3;

Fig. 3 is a longitudinal vertical section of the garage and its operating mechanism for the doors thereof;

Fig. 4 is a vertical section taken on the line 25 4—4 of Fig. 3;

Fig. 5 is a detail vertical section taken on the line 5—5 of Fig. 4; and

Fig. 6 is an enlarged detail vertical section of the catch which secures the door in closed position.

In the embodiment illustrated the building to which the invention is shown applied is indicated at 10 in the form of a garage with the doors shown at 11, said doors being usually outwardly opening double doors. The approach to the garage is shown in the form of a driveway 12 extending flush with the entrance to the garage doors and under which is located a longitudinally extending chamber 13 terminating beyond the garage door entrance inside the garage and at its outer end communicating with a well 14 in which is located a spring projected depressible platform 15, constituting a part of the door opening mechanism. This platform or depressible element 15 is as shown located in the driveway at a point a suitable distance from the door and is hinged at its rear or outer end as shown at 16 and supported at its front end by coiled springs 17 which normally hold the platform raised at its front end and inclined downwardly toward its rear end flush with the driveway as shown clearly in Figs. 1 and 3.

A web-like arm 18 depends from the lower face of the depressible platform 15 and is provided 55 with an apertured ear 19 at its lower end with

which is designed to be connected a rod 20 housed in a tubular casing 21 located in the chamber 13. The inner or front end of this rod is turned upwardly and provided with an eye 22 as shown at Fig. 3 and with which is connected a U-shaped member 23. One arm 24 of this member extends through the garage floor adjacent the point of closing of the doors 11 and is provided with a head 25 for a purpose presently to be described. The other arm 26 of the member 23 is connected with a spring projected bolt 27 slidably mounted in a hanger 28 depending from the garage floor and equipped on its upper end above the floor with a bevelled catch 29 designed to engage a keeper 30 located on the inner face at the lower edge of one of the doors 11.

Both of the doors 11 are equipped with coiled opening springs 31 connected at one end with the door and at their other end with a bracket on the inner face of the garage so that when the doors are released these springs will operate to throw them open into the position shown in Fig. 1.

One of the doors 11 is provided on its inner face with an L-shaped catch member or cross head 32 having a laterally and rearwardly extended slotted foot or lug 33 at its lower end designed to engage the upstanding bolt 24 under the head 25 thereof when the door is in closed position. This member 32 has a laterally extending apertured ear 34 at its upper end with which is engaged one end of an actuating rod 35, the other end of said rod being connected with a spring projected latch member 36 mounted in a housing 37 on the inner face of the door 11. This latch member 36 has a headed stud or arm 38 attached to its inner face, said housing being slotted to permit the arm 38 to slide therein. This latch member 36 is designed when the door is closed to engage a keeper 39 carried by the inner face of the front wall of the garage at the top of the door opening as shown in Figs. 4 and 6.

The rod 35 which connects the L-shaped catch member 32 with the bevelled latch member 36 is of a length sufficient to hold these members so that when latch member 36 is depressed from the closing of the door the slotted foot member 33 will be moved downwardly and caused to straddle the arm 24 of the U-shaped member 23 below the head 25 thereof and the complete closing of the door will permit the latch member 36 to move upwardly into the keeper 39 and thereby securely lock the door both at the top and bottom.

A downward pull on the member 23 caused by the depression of the platform 15 will cause the foot 33 to move downwardly thereby disengag- 110

ing the latch member 36 from the keeper 39 and the coiled spring 31 on the door will force the door open thereby disengaging the foot from the bolt 24 and the door will automatically open. This downward pull on the member 33 also operates to draw down the catch 29 out of engagement with the keeper 30 on the other door thus releasing that door which under the action of spring 31 will fly open in the same manner as the one above described. The doors being open the car may be driven into the garage and the doors may be manually closed against the tension of the springs 31 when the driver leaves the garage.

15 The doors will remain open until manually closed and after the car has been housed for the night this may be done and when it is desired to again use it stepping on the platform 15 will open the doors and permit the driver to take out his car.

20 Without further description it is thought that the features and advantages of the invention will be readily apparent to those skilled in the art.

25

80

and it will, of course, be understood that changes in the form, proportion and minor details of construction may be resorted to, without departing from the spirit of the invention or its scope as claimed.

I claim:

A latch release mechanism for doors comprising a reciprocating rod mounted on a spring-pressed door, a latch means connected with one end of the rod, a cross head connected with the other end of the rod and having a slotted lug, means provided with an arm having a head adapted to be received by the slotted lug with the head engaged by said lug, said arm adapted to be reciprocated for reciprocating the rod, a reciprocating means for the arm, the head and lug cooperating with the latch means for retaining the door in closed position, and means connected with the arm for retaining a second spring-pressed door in closed position and releasable when the reciprocating means is operated to permit the spring to open the second door.
